CHAIR OR THE LIKE

Miguel Rodrigo, Republica de Chile St. 284,
Lima, Peru

Filed Oct. 23, 1965, Ser. No. 87,886

Term of patent 14 years

(Cl. D15—1)

FIG. 1 is a side elevational view of a chair showing my design, the side opposite being a mirror image thereof; FIG. 2 is a front view; and

FIG. 3 is a perspective view.

The essential features of my design reside in those portions shown in full lines on the drawing.

I claim:

The ornamental design for a chair or the like, as shown and described.
